CLAIM

The ornamental design for a keyboard with built-in mouse, as shown and described.

DESCRIPTION

FIG. 1 is a perspective view of a keyboard with built-in mouse showing our new design;
FIG. 2 is another perspective view thereof;
FIG. 3 is a front elevational view thereof;
FIG. 4 is a rear elevational view thereof;
FIG. 5 is a left side elevational view thereof;
FIG. 6 is a right side elevational view thereof;
FIG. 7 is a top plan view thereof;
FIG. 8 is a bottom plan view thereof;
FIG. 9 is an enlarged view of portion 9 shown in FIG. 1;
FIG. 10 is an enlarged view of portion 10 shown in FIG. 1; and,
FIG. 11 is an enlarged view of portion 11 shown in FIG. 7. The dash-dash broken lines in the drawings depict portions of the keyboard with built-in mouse that form no part of the claimed design. The dot-dash broken lines represent boundaries of the enlarged portions and form no part of the claimed design.
